Alfred W. Madl, Milwaukee, Wis., assignor to John Oster
Manufacturing Co., Milwaukee, Wis., a corporation of Wisconsin

Application December 15, 1958, Serial No. 53,782

Term of patent 14 years

(Cl. D37—1)

The dominant features of my design reside in those portions thereof shown in full lines.

I claim:

The ornamental design for a combined knife and scissors sharpener, as shown and described.
